Application October 30, 1939, Serial No. 302,007

13 Claims. (CL. 181—48)

This invention is concerned generally with acoustic band stop filters, i. e., devices which, placed in the path of sound, will remove therefrom, or greatly repress, sounds of pitches lying within a definite frequency range, and readily transmit sounds of pitches lying outside of this range.

More particularly this invention is concerned with acoustic filters which, in addition to possessing band stop characteristics as regards the transmission of sound, also have the property of allowing the ready passage of gases, such as air for ventilation, and the like.

Such filters may have a variety of uses; used purely as acoustic filters they can be placed in front of telephone receivers or microphones to repress sounds of undesirable frequencies, or to isolate, for the purpose of measurement, definite bands of frequencies of an admixture of sounds or noises; used otherwise, they can be placed in ventilating ducts or apertures to repress motor or blower noises, or to prevent, where a ventilating duct communicates with several rooms, noises from being transmitted from one room to another; they may be placed in windows to allow the entrance of air but shut out street noises, or in transoms to shut out hall noises, etc.

One of the objects of this invention is to provide a form of acoustic band stop filter of readily variable characteristics, that is to say, a form such that the band width and cutoff frequencies can be predetermined readily to suit the particular purpose for which the filter is to be used. Another object is to provide an acoustic band stop filter which will produce a maximum repression of frequencies lying within a certain range and yet transmit with a minimum of impedance frequencies outside this range. Further objects are to provide a form of acoustic band stop filter which is readily adaptable to any size or shape of aperture, also one which is simple and inexpensive to manufacture.

Additional objects of the invention are to provide forms of acoustic band stop filters which will be effective at relatively low frequencies; and also to provide forms which will be effective on nonplanar sound waves.

Further and other objects will become apparent as the description is read in connection with the accompanying drawings, in which—

Fig. 1 is a sectional elevation of a building with an air conditioning and ventilating system associated therewith, all shown more or less diagrammatically, the ventilating system being provided with sound repressing filters;

Fig. 2 is a diagrammatic view of the proportioning of the heights of the filter ducts in the case of a filter of rectangular cross section;

Fig. 3 is a similar view for the case of a filter of circular cross section;

Fig. 4 is a perspective view of one form of band stop acoustic filter in accordance with my invention;

Fig. 5 is a horizontal cross section of the same;

Fig. 6 is a graph of the characteristic curve of a filter of the type shown in Figs. 4 and 5;

Fig. 7 is a graph giving the relation between the cutoff frequencies and the spacing of the filter plates for a filter of the type shown in Figs. 4 and 5;

Fig. 8 is a graph showing the relation between the lower cutoff frequency and the depth of the filter grooves for a filter of the type shown in Figs. 4 and 5;

Fig. 9 is a perspective view of a portion of a modified form of acoustic filter, namely one in which pairs of adjacent slots have been united into a single passage;

Fig. 10 shows more or less diagrammatically a form of filter particularly adapted to construction of sheet metal;

Fig. 11 shows a form of cover plate to be used when it is desired to filter out low frequencies;

Fig. 12 is a horizontal cross section of a filter adapted to filter out low frequencies;

Fig. 13 shows an alternative form of cover plate;

Fig. 14 is a cross section of a filter plate for low frequencies, particularly adapted to manufacture by extrusion or molding;

Fig. 15 is a cross section of a filter plate also for low frequencies adapted to manufacture from sheet metal;

Fig. 16 is a cross section of a filter plate assembled also for low frequencies adapted to be manufactured from a special form of channel;

Fig. 17 is a perspective view of a filter plate particularly effective on nonplanar waves;

Fig. 18 shows a perspective view of an alternative form of filter plate for the same purpose;

Fig. 19 shows a perspective view of a form of acoustic band stop filter, particularly effective on nonplanar waves;

Fig. 20 is a front elevational view of an acoustic filter of variable band width;

Fig. 21 is a side elevational view of the same;

Fig. 22 is a perspective view of a special calibrated adjusting nut used in the filter of Figs. 20 and 21;

Fig. 23 is a perspective view of a special resilient washer used in the filter of Figs. 20 and 21;

Fig. 24 is a side elevational view of the stringer bar used in the filter of Figs. 20 and 21;

Fig. 25 is a diagrammatic view of a form of the invention for delivery of air from a high pressure main to a room; and

Fig. 26 is a diagrammatic view of an improved arrangement for delivery of air from a high pressure main to a room.

60 The present invention is capable of various

forms of construction and practical application. In order to disclose one embodiment of the invention, it is shown and described in connection with an air conditioning system, but it is understood that this is by way of example only as the invention is capable of use in various other relations.

In the conventional air conditioning systems for dwellings, offices, hospitals and similar structures, it is necessary to employ slow speed fans or blowers for circulating the air because the high speed fans or blowers are too noisy and the noises conducted to the rooms by the air ducts from these high speed fans or blowers are very disturbing. The use of slow moving blowers is objectionable because of the inefficiency of the operation of such fans or blowers.

The present invention seeks to remedy this difficulty by the provision of new and improved sound filter means that may be interposed in the air ducts between the blower and the rooms for absorbing not only the obnoxious sound waves or noises generated by the blower but also for filtering out objectionable street noises as well.

Referring now to the drawings, in particular to Fig. 1, the reference numeral 20 designates a dwelling or office building having the separate rooms or offices 21 and 22, hallway 23, and the basement 24. The building may comprise any number of rooms but only two have been illustrated in order to simplify the description. Located in some convenient place in the basement 24 is a fan or blower 25 driven by an electric motor 26, which blower supplies air to the rooms 21 and 22 by means of the main supply conduit 27, and the branch supply conduits 28 and 29. Air leaves the rooms through the ventilator openings 31 and 32, and returns to the air conditioner 36 by means of the branch return conduits 33 and 34 and the main return header 35. Before entering the conditioner, the return air is mixed with a certain proportion of fresh air, which enters through the fresh air intake 37. The resulting mixture then passes through the air conditioner 36, which may be adapted to heat or cool and humidify the air before delivery to the blower 25. Instead of being returned to the air conditioner, some of the air may escape from the rooms through the window openings 38 and the transom openings 39. Suitable dampers 41 are provided in the branch conduits 28, 29, 33, and 34 for regulating the flow of air to and from the rooms. In addition, louver valves 42 and 43 are provided in the air intake 37 and the return header 35, respectively, in order to regulate the proportions of fresh and returned air entering the air conditioner 36.

Placed at suitable points in the ventilating system and adapted to fit the various shapes of cross section of the same are acoustic filters according to my invention. In particular, following the blower 25 there is an acoustic filter 44 adapted to fit in the main conduit 27 and designed particularly to filter out fan and motor noises; placed in the conduits 28, 29, 33, and 34 are acoustic filters 45 for the purpose also of filtering out fan and motor noises as well as to prevent noises from being transmitted from one room to another by means of the conduits 27, 28 and 29 or 33, 34 and 35. Placed in the window openings 38 are acoustic filters 46 particularly designed to filter out street noises and permit the escape of air from the building, while in the transom openings 39 are placed acoustic filters 47, particularly designed to filter out hall noises, etc.

The filter consists in general of a number of

ducts of similar construction ranged alongside one another, i. e. in parallel, the exact number being determined in a given case by the conditions to be met; for example, the impedance which the filter as a whole is to offer to the transmitted sound or stream of air. In general, the greater the number of ducts, the greater the effective aperture of the filter and the lower its impedance. The height of the individual ducts and 5 the total number of ducts will depend also on the shape of the aperture, the area which the filter is to cover, etc. In particular if the aperture in 10 which the filter is placed is of rectangular shape, the filter is preferably of like shape, the individual 15 ducts all having the same height as in Fig. 2; while for other shapes of apertures the height of the individual ducts will preferably conform to the height of the cross section at any point, as shown in Fig. 3, which shows a preferred proportioning of the ducts for a circular aperture.

In the form of the construction shown in Figs. 4 and 5, which is by way of example only, the filter comprises the frame 51, which in the form shown is rectangular in shape and has, what for 20 convenience of description will be termed, the upper and lower frame members 52 and 53 and the end members 54 and 55. Mounted within the frame are a plurality of vertical partitions 56 spaced apart and from the end walls 54 and 55 25 to form parallel passages or ducts 57 rectangular in cross section, along which the air and sound waves travel from the front toward the back of the filter. Each partition is provided on each of its sides with a plurality of vertical grooves or 30 slots 58, Fig. 5, which are preferably, though not necessarily, rectangular in cross section, and which extend in a direction perpendicular to the axis of transmission of the duct. The inner 35 faces of the end members 54 and 55 are also provided with a plurality of vertical grooves 59 similar to the grooves 58.

The filter, provided where necessary with a suitable baffle, or shield, not shown, to prevent sound from by-passing around it, or adapted to entirely 40 fill the aperture of a conduit if used therein, is placed in the path of the sound wave with the axes of the ducts parallel to the direction of transmission of the sound wave.

In Fig. 3 is shown a filter of this same type 45 adapted to a circular opening. In this form of construction the partitions 56a and the ducts 57a differ from the corresponding parts of Fig. 4 in that in Fig. 3 the vertical dimensions of the ducts 57a at any point conform to the height of the cross section at that point, the height of the ducts 55 decreasing from the center line of the section outward toward either side.

I have discovered that such devices will act as 50 effective acoustical band stop filters; and I have 55 determined experimentally how the characteristics of these filters depend on their constructional details and dimensions.

Before disclosing these results, it will be convenient to designate certain dimensional constants, or parameters, of the filter and also certain acoustical quantities by symbols, as follows:

I shall let H , L , and D represent the internal height, length, and width, respectively, of the 60 ducts 57; T , the thickness of the vertical partitions or filter plates 56; d and w the depth and 65 width, respectively, of the grooves or slots 58 in the faces of the filter plates; s the distance between centers of two adjacent grooves or slots 70 58; n , the number of grooves or slots per face of the duct; f , the lower cut-off frequency of the 75

filter; F , the upper cut-off frequency; and b , the band width of the filter, i. e., $F-f$.

A typical transmission curve of a filter of the type shown in Figs. 4 and 5 is given in Fig. 6, in which the ordinates represent the fraction of transmitted sound energy plotted to a logarithmic scale; and the abscissas represent the frequencies in cycles per second. The particular curve is that corresponding to a filter for which $T=1.0$ cm., $D=8.0$ mm., $H=30$ cm., $L=53.2$ mm., $d=7$ mm., $w=2$ mm., and $n=7$.

It will be seen that the device suppresses very markedly all frequencies in a certain range and readily transmits frequencies outside of this range, i. e. acts as a band stop filter. Its effectiveness is attested by the fact that the attenuation within the band exceeds 60 decibels, which means that within the band less than one millionth of the incident energy is transmitted.

Of primary importance in a filter of this type are the lower cutoff frequency f , the upper cutoff frequency F , and the band width b , that is $F-f$. I have found that these quantities can be readily varied and adjusted to predetermined values by changing certain dimensional constants or parameters of the filter, as follows:

Of marked effect on the cutoff frequencies f and F is the dimension D . The manner in which f and F vary with D , other factors being constant, is shown in Fig. 7. It is seen that as D is increased, i. e., as the filter plates 56 are spaced farther apart, the upper cutoff frequency decreases continuously, while the lower cutoff frequency increases rapidly at first, then more slowly, and eventually reaches a constant value, which does not change with further increase in the spacing of the plates. From this it will be seen that when the plates 56 are spaced relatively far apart the band width will be narrow; while when they are spaced relatively close together, the band width will be wide. It will also be seen that above a certain critical spacing the upper cutoff frequency alone varies with the spacing; while below this critical spacing both cutoff frequencies vary with the spacing.

Of marked effect on the lower cutoff frequency f , is the dimension d . The manner in which f varies with d , or more specifically $1/d$, is shown in Fig. 8. It is seen that as $1/d$ increases, that is as the depth of the grooves 58 decreases, the lower cutoff frequency increases. If therefore, it is desired to extend the lower cutoff frequency to lower frequencies the slots 58 would be made deeper.

By varying the two dimensions D and d then, it is possible to vary greatly the characteristics of the filter, and adapt it to many specific purposes, in accordance with certain of the objects of this invention.

The other dimensional constants or parameters of the filter are of secondary importance: The width w of the grooves is not material as long as w is less than d , and ordinarily will be from $\frac{1}{3}$ to $\frac{1}{2}$ the value of d ; the spacing s of the grooves is not important as long as s is not large compared to the wave length of sound; the value of T affects mainly the transmission outside the band, because for a given value of D , T will determine the fractional part of the filter face which is open; the same can be said of H ; the value of L is important only as it determines the number n of the grooves. The number n determines primarily the degree of attenuation of the suppressed components of sound; the larger n is,

the steeper will be the cut-off, and the greater the attenuation within the band.

While I have shown grooves on both of the internal faces of the duct, it must be understood that a duct with grooves on only one surface will also act as a filter but will be only half as effective. Also while I have shown the grooves in opposite sides of the filter duct to be in line, it should be understood that this is not a necessary condition for an effective action of the filter but merely makes for convenience in manufacture.

It should be noted that my filter operates upon a basic principle entirely different from ordinary acoustical attenuation devices, such as sound labyrinths and sound absorbents. These latter devices operate upon the principle of acoustic resistance, as they absorb the sound energy in a manner analogous to the absorption of power by friction in a machine or to the absorption of electrical energy by resistance in an electrical circuit. My device, however, is a reactance type acoustic filter, employing a principle known as acoustic reactance in which the energy of one sound wave is used to neutralize the energy of a following sound wave without substantial absorption.

To differentiate between these two basic types, it may be said that filters operating upon the principle of acoustic resistance dissipate the sound energy without affecting the phase relationship of the sound waves. An acoustic reactance, however, throws the sound waves out of phase in such manner that the sound energy is no longer propagated in its original direction.

An acoustic reactance, however, does not absorb, decrease or dissipate, in any manner, the incident sound energy. Sound labyrinths and sound absorbents both operate on the principle of acoustic resistance, for in a sound labyrinth

the sound is forced to travel a relatively great distance before emission and utilizes the resistance of the air to absorb the sound energy. Ordinary sound absorbents, such as glass wool, or felt pads are well-known and require no explanation.

Referring to the drawings, sound waves entering the ducts 57 will enter the grooves 58 in the side walls of the duct and will be reflected back into the duct 180° out of phase with the succeeding sound wave. The reflected sound wave provides destructive interference for the next succeeding incident sound wave and thus neutralizes the latter's energy to a degree proportionate to the amount of the energy reflected by the groove. It is to be understood that a certain amount of sound will always be absorbed during its passage through the duct 57 and in the grooves 58 due to the viscosity of the air, but this absorption is largely negligible and occurs in all types of acoustical devices.

From the foregoing explanation it may be seen that I may, by adjustment of the dimensions of the groove, selectively remove sounds of any predetermined frequency and that within reasonable limits the reduction in sound energy effected by my filter will always be a predetermined fraction of the incident sound energy.

It is not to be understood, however, that my filter must be formed entirely of sound reflective material as it may be seen that the base or bottom of the grooves is the principal sound reflecting portion and hence the efficiency of the filter is controlled principally by the sound reflectivity of the exposed base wall of the grooves 58. It is generally conceded that all materials

absorb sound to a certain degree and I may therefore vary the efficiency of my filter by varying the sound reflective properties of the material used to form the walls of the grooves.

I prefer to form the entire filter of a relatively dense sound reflective material such as metal, wood, glass or ceramic, but, if desired, the body of the filter may be formed of any other convenient material and the inner walls of the grooves, or only the bottom or base wall of the grooves, may be formed of a sound reflective material, such as those mentioned above. If the body of the filter is formed of a sound absorptive material, it is obvious that the filter will not be as sharply selective as it will be if the body of the filter is formed from a sound reflective material.

When a plane sound wave passes through the filter of Figs. 4 and 5, the disturbances at any instant at corresponding points such as P, P' (Fig. 5) of two adjacent slots on a line transversely of the filter are in phase, which means that the dividing portions *a* could be removed and the slots moved together and joined to form a common slot without impairing the action of the filter.

This leads to a form of construction shown in Fig. 9. Provided all dimensions, except T which is made equal to 2d, are retained, such a filter would duplicate very closely the characteristics of the filter of Figs. 4 and 5.

The filter of Fig. 9 is constructed conveniently by replacing each of the vertical slotted filter plates 56 of Fig. 5 by an assembly 61 of vertical, parallel laths 62 of rectangular cross-section, each lath being provided with apertures 63 for mounting on stringer bars 64 with interposed spacer washers 65, the stringer bars being threaded at their ends 66 to accommodate clamping nuts 67 and washers 68. The width of the transverse passages 69 may be varied as desired by varying the thickness of the spacer washers 65. The partitions may be spaced closer or farther apart by adjusting them in any suitable manner along the top and bottom plates 52 and 53. The individual assemblies or filter elements are mounted by securing them to the upper and lower frame members 52 and 53 by any suitable means. The end members 54 and 55 may remain as before.

A form of filter plate 71 which lends itself readily to production from sheet metal is shown in Fig. 10. In this form, each of the vertical filter plates 56 of the filter of Fig. 5 is replaced by a sheet metal structure or filter element 71 bent into the shape shown to provide slots 72 alternately on opposite sides of the structure. The structures 71 can be mounted by securing them to uprights 73 which are secured in turn to the frame members 52 and 53, or the structures 71 can be provided at their ends with suitable flanges (not shown) for securing them directly to the frame members 52 and 53.

A difficulty with the forms of filter described so far is that when it is desired to filter out very low frequencies, the depth *d* of the grooves has to be made large, with consequent increase in dimensions of the filter, which may then become too bulky.

I have discovered, however, that the working range of the filters described can be shifted to lower frequencies by providing the slots 58 (Fig. 12), with constricted entrance ports. These may take the form of parallel slits 75 in thin cover plates 74, mounted one on each side of the ver-

tical partitions 56, the slits being so arranged and spaced that there is one down the center line of each slot, as shown in Figs. 11 and 12.

In place of the slits, rows of circular apertures 76 in cover plates 74a can also be used as in Fig. 13, in order to shift the working range of the filter to lower frequencies.

By the addition of the entrance ports the original plain grooved filter plate is converted into a plate comprising a multiplicity of enlarged inner chambers 58 and communicating constricted entrance ports 75 and 76. In manufacture, of course, the cover plates 74 or 74a could be cast integrally with the partitions 56.

Since for low frequencies the inner chambers 58 will be of relatively large dimensions, for economy of space, a filter plate 71 of the cross section shown in Fig. 14 is preferably used for low frequencies, and manufactured conveniently by casting or moulding a suitable material directly into this shape.

With sheet metal the form of filter plate 78 shown in Fig. 15 is preferably used. These plates may be made from a single sheet of metal as shown, and mounted by securing them to suitable supports 79.

Filters for low frequencies could also be economically built up of rows of units 80 of the cross section shown in Fig. 16, each of the filter plates 56 of the original filter being replaced by a row of elements 80.

The elements 80 are straight, thin-walled conduits of rectangular cross section and identical dimensions, each of which carries a slot 88, parallel to the axis of the conduit, in one face. The slots are of identical dimensions and similarly placed in all the conduits.

The forms of filter so far described are primarily for use in cases where the incident wave front is plane or very nearly so. They will be effective on nonplanar waves to a degree which depends on the extent of the departure of the wave front from the planar state. Where this departure is marked, the forms of filter plates and filters now to be described will be more effective.

A form of filter plate for nonplanar waves is shown in Fig. 17. It comprises a plane plate 81 provided with a multiplicity of perforations 82 of rectangular cross-section extending partially or completely through the plate. The composite filter using these plates would be built up as the filter of Figs. 4 and 5 except that the plates 81 would replace the plates 56 and plane unperforated plates would replace the end members 54 and 55.

An alternative form of filter plate for nonplanar waves comprises a plane parallel plate 83 provided with a multiplicity of circular holes 84 extending partially or completely through the plate.

Another form of filter effective on nonplanar waves is shown in Fig. 19. It comprises a thick plate 85 with a multiplicity of ducts 86 of square cross section extending therethrough, each duct being provided with slots or grooves 87, preferably of rectangular cross section, on all four of its inner faces 89. The plate 85 is placed in the path of the sound wave to be filtered.

A modified form of the invention, namely a band stop acoustic filter of variable band width, is shown in Figs. 20 and 21. It is clear from the graph of Fig. 7 that the band width of a filter of the type shown in Figs. 4 and 5 depends upon the spacing of the filter plates 56, and therefore

can be made variable, provided the filter is so constructed that the spacing of the filter plates is capable of variation. In the form of filter shown in Figs. 20 and 21 this is accomplished by interposing resilient spacer washers 91 between the separate filter plates 92 and also between the end members 93 and 94 and those of the filter plates 92 nearest to them. The filter plates 92 and end members 93 and 94, which otherwise may be identical with the filter plates 56 and end members 54 and 55, respectively, of Figs. 4 and 5, are provided at the four corners with circular holes 95 adapted to pass with a sliding fit round stringer bars 96.

The resilient spacer washers 91 (Fig. 23), which are preferably circular in form, all have identical dimensions and are cut from material of identical resilient properties, so that equal pressures applied to their faces will result in equal compressions for all of them. They are provided with circular holes 97 somewhat larger in diameter than that of the stringer bar 96 to allow for change in diameter on compression.

The stringer bars 96 (Fig. 24) have a disc-like head 98 at one end; which head is provided with screw holes 99; while at the other end they are threaded to receive a specially shaped nut unit 100. The latter (Fig. 22) consists of a flat calibrated disc 101 to which is attached rigidly a somewhat smaller nut shaped part 102. The disc 101 is provided with a scale 103 near its periphery. Nut and disc are preferably made in one piece.

The filter plates 92, 93 and 94 are mounted parallel by means of the stringer bars 96 and interposed spacer washers 91, the heads 98 being rigidly secured to the end plate 93 by means of small screws 113 through the holes 99. After assembly, the plates 92, 93 and 94 are secured by tightening the nuts 100, a metallic washer 104 preferably being interposed. The nuts 100 are initially adjusted so that all the resilient washers 91 are equally compressed, and an index finger 105 is then placed in position at the zero line of the scale. Subsequently equal rotations of the nuts 100 will produce equal compressions of the spacer washers 91 and result in equal variation of the spacing of the filter plates 92, 93 and 94.

The resulting assembly 106 is closed at top and bottom by means of the upper and lower cover plates 107 and 108, which are provided with retaining flanges 109. The end plate 93 is secured rigidly to the cover plates by screws 114. The edges 110 of the filter plates 92, 93 and 94 and the inner surfaces 111 of the plates 107 and 108 as well as of the flanges 109 are carefully fitted, so that the plates 92 and the plate 94 may slide freely on the retaining plates 107 and 108. The assembly is provided on the side of the plate 94 with a cover plate 112 of sufficient width to allow the assembly 106 to contract laterally without allowing the bypassing of sound around the side of the filter.

It is also possible to construct a filter so that the lower cutoff frequencies may be varied within prescribed limits. This may be accomplished by employing a filter of the type shown in Fig. 9, but separating the laths 62 by small rectangular rubber strips extending from top to bottom, along the center line of the lath assembly 61. With such an arrangement the depth of the transverse grooves may be varied merely by tightening the nuts 67, causing the strips to be compressed to effectively reduce the depth of the grooves.

Another modification of my invention as shown in Fig. 25, is concerned with the suppression of noises in the delivery of air from high pressure ventilating conduits to rooms and offices. In order to maintain the pressure in a high pressure ventilating conduit 121 supplying a room 120, it is necessary to pass the air through a number of constricted openings, such as for example, the slits 122 of a louver valve 123. However, the passage of air under pressure through such constrictions is attended by the production of considerable noise, which may be objectionable to the occupants of the room or office which the conduit supplies. In order to avoid this difficulty, in one form of my invention, the constricted louver valve 123, leading from a high pressure ventilating conduit 121 is followed by an expansion chamber 124, and before entrance into the room the air rushing through the slits 122 is passed through a filter 125 of the type of Figs. 4 and 5 with a cross-section relatively large to that of the conduit 121 and with a relatively large number of filter ducts 51, so that it is adapted to filter out noises generated by the rush of air through the slits of the louver valve and yet offer a minimum of impedance to the flow of air. It is to be understood of course that this form of the invention is not limited to louver valves with narrow slits but can be used with any equivalent device having a multiplicity of constricted openings through which air under pressure is allowed to stream. The louver valve may be replaced, for example, by a plate with a series of narrow slits, or a plate with a multiplicity of small apertures, etc.

In the improved form of the invention shown in Fig. 26, the louver valve of Fig. 14 is replaced by an acoustic filter of the type of Figs. 4 and 5. In this arrangement, a high pressure main 131 delivers air to a room through an acoustic filter 132, an expansion chamber 133, and a second acoustic filter 134. The acoustic filter 132 is constructed with relatively few filter ducts in order to maintain the pressure within the main 131, while the filter 134 is constructed with a relatively large number of filter ducts. The filter 132 serves to filter out any fan or motor noises attempting to pass into the room from the high pressure main as well as to maintain the pressure in the main; while the filter 134 serves in turn to filter out any noises created by the air streaming from the high pressure main through the filter 132 into the expansion chamber.

In most air conditioning systems, because of the fact that a low speed blower is necessary to reduce objectionable noises to a minimum, the distribution of air in the duct system is accomplished by deflectors which depend upon air velocity for their effectiveness. As a result it is virtually impossible to have branch ducts connect with the main duct at angles of 90 degrees or less with respect to the direction of air flow. By using a high speed fan, however, in conjunction with sound filters of type disclosed in this application, and creating pressure within the main duct in order to effect distribution of air to the branch ducts, it is possible to have the branch ducts connect with the main duct at any angle that is most convenient for the particular installation.

I claim:

1. An acoustic filter comprising a pair of filter elements mounted in spaced relation, each of said filter elements comprising a sequence of straight

bars of rectangular cross section and identical dimensions, means for mounting said bars in line, and means for holding said bars in spaced relation.

2. An acoustic filter comprising a pair of plane plates mounted parallel to each other and in spaced relation, at least one of said plates being provided internally with a plurality of parallel, straight and relatively elongated chambers of constant cross section, and a plurality of relatively constricted entrance ports leading from the surface of said plate to said chambers.

3. An acoustic filter comprising a pair of plane plated mounted parallel to each other and in spaced relation, at least one of said plates being provided internally with a plurality of parallel, straight and relatively elongated chambers of constant and identical cross section, and a plurality of relatively constricted entrance ports leading from the surface of said plate to said chambers.

4. An acoustic filter comprising a duct of rectangular cross section, at least one internal face of which is provided with a plurality of straight slots of rectangular cross section extending lengthwise in a direction perpendicular to the axis of the duct, a plurality of elongated chambers of rectangular cross section extending lengthwise in a direction parallel to said slots and so located as to communicate one with each slot, the cross section of said chambers being enlarged relatively to the width of the slot.

5. An acoustic filter comprising a duct of rectangular and relatively elongated rectangular cross section, a plurality of relatively elongated chambers of rectangular cross section ranged laterally of said duct, and a plurality of relatively constricted entrance passages connecting said chambers with said duct.

6. In an air conditioning system, the combination of a duct system including a main duct and a plurality of branch ducts, each of the branch ducts being provided with a restricted opening into an expansion chamber, a blower adapted to deliver air under pressure into the duct system, and a sound filter in the expansion chamber, said sound filter of the reactance type comprising a body having a plurality of openings for the transmission of air and grooves in the walls of the openings extending lengthwise in a direction which is perpendicular to the axis of transmission of the air, and having sound reflecting surfaces, said sound filter being adapted to prevent the passage of only a selected band of sound waves.

7. A selective band type sound filter in the form of a duct including a rigid element supported in spaced relationship to a wall of the duct the surface of the element facing the duct wall having formed therein an elongated groove having a sound reflecting bottom wall spaced inwardly from the surface of the element a distance substantially equal to one-fourth the wave length of the sound of lowest frequency to be attenuated, the groove being disposed approximately transverse to the axis of sound propagation through the duct.

8. A selective band type acoustic filter in the form of a duct including a smooth and rigid plate of high apparent density facing one of the inner surfaces of the duct, the plate having a plurality of parallel right angle bends forming a plurality of elongated grooves of regular cross-section alternately on opposite faces of the plate

whereby sounds having wave lengths substantially equal to four times the depth of the grooves will be attenuated while passing through the duct.

5 9. A selective band type acoustic filter including a plurality of substantially rigid elements supported in spaced relationship to each other defining passageways, the opposing faces of each element having formed therein a plurality of elongated grooves of substantially constant cross-section, each of said grooves being transverse to the axis of transmission of the passageways, each groove having substantially smooth sound reflecting walls, the depth of the grooves being not

10 greater than one-fourth the wave length of the lowest sound frequency in the attenuated band and means for varying the effective width of the passageways between the elements.

10 10. A selective band type acoustic filter in the form of a duct including a rigid member having an exposed surface within the duct, said surface having formed therein a plurality of elongated grooves having exposed relatively smooth sound reflective walls, said grooves being of constant cross-section and having their major axes transverse to the direction of sound transmission through the duct, the filter being characterized by a direct variation between the lower band cut-off limit and the depth of the groove.

30 11. A selective band type acoustic filter including a plurality of substantially rigid elements supported in spaced relationship to each other defining passageways, the opposing faces of each element having formed therein a plurality of elongated grooves of substantially constant cross-section, each of said grooves being transverse to the axis of transmission of the passageways, each groove having substantially smooth sound reflecting walls, the depth of the grooves being

35 not greater than one-fourth the wave length of the lowest sound frequency in the attenuated band and means including resilient members interposed between the rigid elements for varying the effective width of the passageways between the elements.

45 12. A selective band type sound filter in the form of a duct having a rigid element supported in spaced relationship to a wall of the duct at least the surface of the element facing the duct wall having formed therein a plurality of elongated grooves having sound reflecting bottom walls spaced inwardly from the surface of the element a distance substantially equal to one-fourth the wave length of the sound of lowest frequency to be attenuated, each of said grooves being of substantially constant cross-section and disposed approximately transverse to the axis of sound propagation through the duct.

55 13. A selective band type acoustic filter in the form of a duct including a plurality of rigid elements supported in spaced relationship to a wall of the duct and to each other the faces of each element having formed therein a plurality of elongated grooves of substantially constant cross-section, each groove having a substantially smooth sound reflecting bottom wall spaced inwardly from the surface of the element a distance not greater than one-fourth the wave length of the sound of lowest frequency to be attenuated by the filter, each of said grooves being disposed transversely to the axis of sound propagation to the duct.

HAROLD K. SCHILLING.

CERTIFICATE OF CORRECTION.

Patent No. 2,299,112.

October 20, 1942.

HAROLD K. SCHILLING.

It is hereby certified that error appears in the printed specification of the above numbered patent requiring correction as follows: Page 6, first column, line 14, claim 3, for "plated" read --plates--; line 47, claim 6, strike out "of the reactance type" and insert the same before "in the" in line 46, same claim; and that the said Letters Patent should be read with this correction therein that the same may conform to the record of the case in the Patent Office.

Signed and sealed this 24th day of November, A. D. 1942.

Henry Van Arsdale,

(Seal) Acting Commissioner of Patents.
